CLAIM

The ornamental design for a milk warmer, as shown and described.

DESCRIPTION

FIG. 1 is a top view of a milk warmer showing my new design;

FIG. 2 is a rear view thereof;

FIG. 3 is a perspective view thereof;

FIG. 4 is a bottom view thereof;

FIG. 5 is a right view thereof;

FIG. 6 is a front view thereof; and,

FIG. 7 is a left view thereof.

(Continued)

The broken lines shown in the drawings are for illustrative purposes only and form no part of the claimed design.

1 Claim, 7 Drawing Sheets
